CENTRIFUGAL AMALGAMATOR AND SEPARATOR

Filed Sept. 6, 1927

Inventor:

Paul A. Neumann

UNITED STATES PATENT OFFICE

PAUL A. NEUMANN, OF CHICAGO, ILLINOIS

CENTRIFUGAL AMALGAMATOR AND SEPARATOR

Application filed September 6, 1927, Serial No. 217,722, and in Canada September 18, 1926.

The invention relates to a centrifugal amalgamator and separator for extracting precious metals from sands and from finely milled ore.

The object of my invention is to provide a machine of the kind mentioned above which, although comparatively simple of construction, makes possible a very high extraction of values from the worthless material accompanying them.

In the accompanying drawing I only show the rotating drum being the essential part of the machine, as the foundations, pulleys, launders and other parts can be arranged in any suitable manner.

While the drawing illustrates an embodiment of my invention, it is to be understood that, in adapting the same to meet different conditions and requirements, various changes in form, proportion, and minor details of the construction may be resorted to, without departing from the nature of my invention.

One form of the invention is illustrated in the drawing, in which Fig. 1 is a vertical section of the drum; Fig. 2 is a vertical section, enlarged, of a modified type of the trap around the top of the drum.

1 is the inlet pipe for the water-mixed material to be treated, from now on called pulp. 2 is the cylindrical wall of the rotating drum. 3 is an inward projecting rim around the top of the drum. An inward projecting shoulder 4 is formed around the base of the walls 2, into which shoulder the curved end 5 of the bottom 6 of the drum merges. 7 is an outlet hole for the mercury, amalgam, and precious metals, to be screwed open only when the machine is stopped. 8 are a plurality of radial vertical vanes to impart the rotation to the pulp. 9 is a cone mounted on the arms 14 to force the streaming pulp downward. The arms 14 are fixed to the stublike prolongation 13 of the spindle 15. 16 are a plurality of discs 45 around the stub 13; by taking them out the

cone 9 can be lowered. 10 is a circular pocket forming a trap around the top of the drum. 11 is the upper rim of this trap. 12 is a mercury lining formed against the walls 2 by the rotation. 17 are a plurality of vertical vanes fixed to the wall 2 to impart the rotation to the mercury and the pulp. In Fig. 2 18 is a wire screen closing the circular opening of the trap 10.

When the machine is working all the parts shown in the drawing, with the exception of the inlet pipe 1, rotate at a high speed.

Before the machine is started a quantity of mercury is put into the drum sufficient to furnish a lining against the walls of the drum entirely filling the space between the shoulder 4 and the rim 3.

By the rotation the mercury flows over the curve 5, and is lined up against the walls 2 of the drum, forming a thin body flush with the rim 3 and the shoulder 4 which, though theoretically paraboloidal, at a high speed of rotation may be called cylindrical for practical purposes. Any surplus of mercury flows out over the rim 3 which, like the shoulder 4 whereon the mercury lining finds a support, is preferably not more projecting inwards than the thickness of the mercury lining.

The pulp is then run in through the inlet pipe 1, and is rotated by the vanes 8. These vanes 8 however, as also the vanes 17, are, in some cases, not necessary, the pulp and the mercury being sufficiently rotated by mere friction with the bottom 6, the cone 9, and the walls 2. The pulp now flows through the circular outlet between the bottom 6 and the cone 9. Striking against the curve 5 the stream of pulp is deflected upwards, so that it cannot rush straight against the mercury, thus avoiding flouring and undulation of mercury. The pulp, spread out into a thin film, assumes a flow practically vertical, becoming parallel to the

mercury lining before flowing onto it. The depth of the pulp film varies with the speed of rotation, but, by taking out the discs 16 below the cone arms 14 and thereby lowering the cone 9, it can also be regulated.

The pulp now flows upwards over the mercury either vertically or in a more or less steep spiral line, according to the rotation imparted to the pulp in relation to that of the mercury.

10 The pulpstream flows in an even thin sheet over the smooth and unbroken surface of the mercury. Any turbulent motion in flowing onto and off the mercury is avoided, as the mercury is flush with the rim 3 and the shoulder 4. By the centrifugal force all substances heavier than mercury, such as gold, platinum, and others, are pressed into the mercury and through it 15 against the walls 2 of the drum, or, if amalgamable, they are amalgamated. The lighter particles of the pulp, the inner edge of which is preferably pointed or rounded to prevent the settlement of solids thereon, 20 such as quartz sand, slimed gangue or other minerals remain swimming on the inner surface of the mercury lining, and continue their way gliding upwards over it, till they 25 are washed out over the rim 3.

30 The volume of the precious metals thrown into the mercury causes some mercury to flow over the rim 3. Any mercury so displaced, sometimes carrying values of precious metal dissolved in it, is thrown into the trap 10, forcing on account of its higher specific gravity its way into the sands and slimes partly filling that trap. The trap consists of a circular pocket around the top of the drum, and spaced substantially outwards, so that the pulp flowing out over the rim 3 does not flow quietly into the trap, but that it is splashed into it with force, splashing the lighter valueless particles out of it. In order to reduce too strong splashing a wire fabric 18, as shown in Fig. 2, may be placed over the opening of the trap. The same result of reducing too strong splashing may also be obtained by making the connection from the rim 3 to the trap upwardly inclined, as shown in Fig. 2.

This connection from the rim 3 to the trap must always be of such incline that no solids from the pulp can settle thereon under the influence of centrifugal force.

As said before, the vanes 8 and 17 may be left away. In such case the pulp, being less rotated than the mercury, would flow over it in a spiral, remaining consequently longer in contact with it during its passage through the drum.

When the operation is finished, and the drum is stopped, the mercury, the amalgam, and the precious metals will be found on the bottom of the drum and in the trap, from

whence they can be removed through the hole 7 or in any suitable manner.

I am aware that amalgamators and separators are known in which the pulp flows over a mercury lining formed by the rotation in a cylindrical drum. All these devices show great disadvantage, which render their working defective or impossible. Some of them have riffles projecting over the mercury, thereby causing an accumulation of solids against these riffles, through which fresh pulp cannot come any more in contact with the mercury. Others direct the pulp-stream more or less fully against the mercury, whereby this is floured and washed into the waste, no effective means to catch it being provided. Others again provide a circulating mercury surface, forcing the mercury to pass through narrow channels and other obstacles breaking it up into minute globules. Besides, such machines are very heavy having double walls. They are extremely complicated and expensive, and, the mercury being kept in circulation, they require an excessive driving power.

My invention differs from all these, being a very simple, comparatively inexpensive device. Riffles and other impediments to the upward flow of the pulp are avoided. No solids can settle against the upper rim of the machine, as the mercury is flush with it. Any precious metals, escaping from being caught within the drum, are caught in a rotating trap, and so is also any mercury and amalgam, which is displaced from the drum by the precious metals caught there. By using an uninterrupted mercury lining, the lower edge of which is protected against the onrushing pulpstream and the surface of which is unbroken and is flush with the rims bordering it, I can apply a very high centrifugal force without fear of flouring mercury and of accumulating solids on it detrimental to the extraction. And by combining this with the trap, catching the unavoidable overflow of mercury loaded with precious metal, I obtain a very much increased efficiency in amalgamation and separation.

In the drawing the rim 3 is shown made in one piece with the trap, and so is the shoulder 4 in one piece with the curve 5. It would of course be no departure from the nature of my invention if the rims were made in one piece with the walls 2, or if they were made of separate pieces by themselves. 120

I claim:

1. In a centrifugal amalgamator and separator of the type having a rotating drum with practically cylindrical walls, the combination of a mercury lining with an unbroken surface kept up against these walls by the rotation, means to protect the lower edge of this lining against the onrushing pulpstream, means to direct this pulpstream parallel to this lining, a rim bordering the 130

upper edge of this lining and determining its thickness, and a mercury trap outwardly spaced around the top of the drum and connected therewith.

- 5 2. In combination, a centrifugal amalgamating and separating receptacle adapted to maintain a wall of mercury within the same during rotation, a trap at the top of the receptacle, and an open meshed screen 10 extending across the mouth of said trap and adapted to receive the impact of material overflowing the receptacle.

PAUL A. NEUMANN.
